UNITED STATES PATENT OFFICE.

EVERETT S. CAMERON, OF BEVERLY, MASSACHUSETTS.

MULTIPLE-CYLINDER EXPLOSIVE-ENGINE.

1,068,481.

Specification of Letters Patent. Patented July 29, 1913.

Application filed April 21, 1911. Serial No. 622,525.

To all whom it may concern:

Be it known that I, EVERETT S. CAMERON, a citizen of the United States, residing at Beverly, in the county of Essex and State of Massachusetts, have invented certain new and useful Improvements in Multiple-Cylinder Explosive-Engines, of which the following is a specification.

My invention consists in the employment 10 of a series of interchangeable ported cylindrical members whose ends are designed to be locked together, so as to form a straight continuous valve structure to control the inlet and exhaust of a plurality of cylinders 15 and another similarly-arranged valve structure to control the exhaust of a like number of cylinders, and a special gearing arrangement to drive both valve structures in one direction.

20 The objects in view are to provide an engine of this class with simple and inexpensive means for governing and regulating the admission of carbureted air into two, four, or more cylinders, and the exhaust thereof, 25 and having the advantage of being formed to facilitate machining, assembling, and interchangeability of the parts. I attain these objects by the construction illustrated in the accompanying drawings, in which—

30 Figure 1 is a side view of an explosive engine partly in section and partly in elevation, showing the manner of mounting my improved intake valve structure, and the gearing arrangement therefor. Figs. 2 and 3 35 are side views of my improved valve structure; Fig. 2 being the valve member designed to be actuated by the gearing arrangement to control the intake and exhaust of one cylinder, and Fig. 3 the valve member for connection with the aforesaid member to control the intake and exhaust of the next adjacent cylinder. Fig. 4 is a cross-section taken on line $x-x$ of Figs. 1 and 5, showing the means for respectively locking 40 each pair of valves. Fig. 5 is a horizontal sectional view taken on line $y-y$ of Fig. 1, showing my improved exhaust valve structure.

45 Like reference characters indicate like parts.

50 My invention is essentially designed for use on the multiple cylinder type of explosive engines, and in the drawings I illustrate two such cylinders a , a , vertically-arranged upon the usual crank-case b , and each cylinder is provided at its upper part with a

central horizontally-arranged integral tubular chamber a^1 which communicates with the usual inlet and exhaust parts (not shown) at its upper portion, and a port a^4 60 at its lower portion, the bore of each chamber a^1 forming a bearing surface for my improved rotary valve structure, presently described. On one side of each cylinder a , about midway its height, is also arranged 65 a horizontal integral tubular chamber a^5 whose bore forms a bearing surface for my improved rotary exhaust valve structure, and said chamber a^5 communicates with discharge openings a^6 , a^6 , in the manner shown 70 in Fig. 5.

75 My improved valve structures consist of two principal members, each designated as a whole by reference characters c^1 and c^2 in Figs. 2 and 3. The member c^1 has a cylindrical body portion c^3 of a length nearly equal to that of the valve chamber a^1 and this body portion is provided with a central transverse opening therethrough to form a port c^4 . Said member c^1 is provided with a concentrically reduced portion at each 80 end, one forming a screw-threaded stem c^5 and the other a connecting portion c^6 which is slotted as shown at c^6 . The member c^2 is 85 constructed the same as the member c^1 above described, excepting, instead of having a stem c^5 at one end both ends are similarly formed with slotted reduced portions 90 c^6-c^6 .

95 Referring to Fig. 1, wherein is shown the manner of mounting the valve members c^1 and c^2 , the stem c^5 of the former member passes through a support d which is secured upon the face of the valve-chamber a^1 , and on the threaded portion of said stem is a nut d^1 which impinges against the side of a spiral gear d^2 to hold the latter fast upon said stem. The body portions c^3 of each valve member c^1 and c^2 fit within the valve chambers a^1 and the end portions abut each 100 other and are connected together by a flat plate or key e , which is inserted through the slotted openings c^6 , c^6 and thereby locks said valve members together. The inner connecting portions c^6 of the valve members c^1 105 and c^2 are inclosed by a bushing f whose ends are secured upon the adjacent faces of the valve chambers a^1 , and the outer disconnected portion c^6 of the valve member c^2 is inclosed by a cap g which is secured upon 110 the face of the valve chamber. The bushing f is designed to prevent displacement of

the key or plate c^4 from the valve portions c^6 . Said bushings f also fit the reduced end portions c^6 of the valves, and being of less diameter than the body of said valves, position the valves centrally in their chambers and prevent the thrusts on adjacent valves. In other words, they form abutments at the ends of each valve chamber.

In Fig. 5 I show the manner of mounting the valve structure for controlling the exhaust from both of said cylinders, through the chambers a^5 , a^5 , and this construction and arrangement of parts are exactly the same as the valve structure above described, except that the diametrical size of these exhaust valve members and their bearings are proportioned relatively smaller, to suit the working condition of the engine. The valves are each provided with suitable packing-rings, as h , h in Figs. 1 and 5, and said valves rotate at one quarter the speed of the crank-shaft i , and each valve is so positioned that its port c^4 stands at an angle of one eighth around from the position of the port of the next following valve.

By having a series of interchangeable valves to control the inlet and exhaust of two, four, six, or eight cylinders, with means for connecting their ends together, as described, affords a flexible joint to allow of expansion and contraction of said valves at points between each cylinder-casting.

The gearing arrangement to revolve each series of valves consists of an upright shaft j which is mounted in bearings of the supports d , d and on said shaft is made fast spiral gears d^3 , which mesh with spiral gears d^2 , to drive each series of valves and with a gear d^5 secured on the end of the crank-shaft i to drive said shaft j . By use of

spiral gears, as described, a silent drive is obtained for the valves. The usual magneto (not shown) is also actuated from the shaft j , by means of a gear on said shaft (not shown), which meshes with the gear l^1 45 on the magneto shaft m . Said shaft j also operates the oil pump n , which is fitted on the lower end portion of said shaft and contained in the forward part of the oil tank b^3 , in order that any leak or overflow from 50 said pump may be returned directly to said tank. The supports for the upright shaft j have each a cover to inclose each engaging pair of spiral gears, as at o and p in Fig. 1. 55

Having now described my improvements, what I claim and desire to secure by Letters-Patent, is—

In an explosive engine having separate cylinders provided each with tubular valve chambers, cylindrical valves to govern the intake and exhaust through said chambers, said valves having slotted reduced end portions extending from each of the valve chambers, a key to fit within the slots of 60 each adjacent valve, a bushing fitting and surrounding the slotted reduced end portions and over the keys and secured to the adjacent faces of said valve chambers, whereby said valves are positioned centrally 65 in said chambers and end thrusts prevented upon adjacent valves, and means to rotate said valves.

In testimony whereof I affix my signature 70 in presence of two witnesses.

EVERETT S. CAMERON.
